WALTER L. FOSTER, OF WHITTIER, CALIFORNIA, ASSIGNOR OF ONE-FOURTH TO ROLAND R. CRUM, OF WHITTIER, CALIFORNIA

AUTOMATIC CATHEAD

Application filed May 5, 1930. Serial No. 449,768.

This invention relates to a cat-head structure having automatic means for winding a line thereon and then releasing the line. Cat-heads are commonly employed in oil well drilling rigs, and one common use is to operate a line attached to pipe tongs for loosening joints of pipe or couplings. In such instances a limited swinging of the tong handle is desirable, and in many instances a repetition of such movement or an oscillatory movement is desirable. Cat-heads which comprise a rotary winding spool are employed to produce an oscillatory movement of the tong handle by securing a cable to the handle and snubbing the cable or rope around the cat-head drum, then releasing the snubbing embrace of the rope upon the drum.

The present invention has for its primary object the provision of a cat-head structure wherein by operation of a control, the line may be anchored to the winding element and will be wound thereon, then automatically released. In addition to the broader object of this invention, there are certain details of design contributing to ease of manipulation, simplicity and compactness of structure.

These objects together with other objects and corresponding accomplishments are obtained by means of the embodiment of my invention illustrated in the accompanying drawings, in which:

Fig. 1 is an elevation of a fragment of a derrick showing my improved cat-head structure, a portion of the operating shaft being broken out to make the view more compact; Fig. 2 is a plan view of the structure shown in Fig. 1; Fig. 3 is a section as seen on the line 3—3 of Fig. 1; Figs. 4 and 5 are views similar to Fig. 3 showing the winding member and coupler in other positions; Fig. 6 is a section as seen on the line 6—6 of Fig. 3; and Fig. 7 is a section as seen on the line 7—7 of Fig. 3.

Referring with more particularity to Figs. 1 and 2, a portion of a derrick is marked 10 and includes posts upon which are mounted bearing blocks 11. Journalled in the bearing blocks is a drive shaft 12 for the cat-head. Overhanging the post 13 is the usual cat-head spool 14. At one side adjacent the post

13 is the cat-head structure embodying my invention and denoted generally by 15. Extending along a cross member 16 and around the post 17 is a control line 18. In Fig. 2, a pipe is marked 19 and a pipe tong 20. A line which may comprise a chain or cable is connected to an eye in the end of the handle of the tong and is marked 21, this line extending to form a part of the line which is to be wound upon the cat-head structure. 22 marks a line connected to a weight, not shown, and forming a counter-balance to return the handle of the tongs to its initial position.

Referring to all of the figures of the drawings, the inner flange of the cat-head spool is in the form of a sheave having a groove 23. The side walls of the groove are notched to provide an abutment tooth 24. Secured to the cross member 16 by a lug is a frame 25 of T form in cross section so as to provide side rails 25a. The frame partially encompasses the sheave and is spaced therefrom. At one end of the frame is a release hook 26 having an inner surface radially inclined in relation to the sheave. The rails end short of the release member as indicated by 27. At the entry or other end of the frame, the rails end as indicated by 28. The middle leg of the frame extends outwardly and has a saddle 29 within which may rest the line, which at this point is shown as formed by a cable 30. Secured to the end of cable 30 is a coupler 31 having rollers 32 adapted to ride on the rim of the sheave and provided with arms 33 arranged so that they may straddle the legs of the frame. Follower pintles 34 extend inwardly from the legs and are adapted to ride either upon the inside or outside of the rails 25a. The rollers 32 are so disposed that they may be placed in engagement with the abutment tooth 24 on the sheave as shown in Fig. 4. Normally the coupler lies in the position shown in Fig. 3 with the rollers 32 disposed out of the path of the abutment tooth 24. Pivotally mounted upon the frame at the entry end is a control slide 35, it being pivoted at 36. A link rod 37 is secured to a bell crank lever 38, the other end of the lever being connected by a rod 39 to a spring 40. The spring 40 is connected to the control line

18 having a ring handle 41 for convenience in operation and adapted to be hooked over a hook 42 on the post 17. The arrangement is such that the slide 35 may be elevated from the position shown in Fig. 3 to that shown in Fig. 4 so as to raise the coupler 31 into position such that the abutment tooth 24 will engage the rollers 32. At the same time, the follower pins 34 will have been raised 10 so as to be in position to be engaged by the underside of rails 25a. The operation of raising the coupler may be performed by pulling upon handle 41.

Assuming that the parts are in the position shown in Figs. 1, 2, and 3, the cable 21 is attached to a pipe tong as shown in Fig. 2. The cat-head is rotated in the direction of the arrow shown in Fig. 3. To cause the line to be wound upon the cat-head, handle 20 41 is pulled to create a tension upon the control line and convey motion to the slide 35 which is then raised to the position shown in Fig. 4 and resiliently held in such upper position by reason of the spring 40. This raising 25 occurs, if the coupler is in registration with the notched portion of the cat-head sheave. If the coupler is not in registration with the notched portion, it will be resiliently held against the rim of the sheave until the cat-head has rotated sufficiently to bring the coupler and notch into registration, whereupon the abutment tooth 24 engages the rollers 32 and begins to wind the line upon the sheave. Pins 34 follow the underside of rails 30 25a and winding continues until the coupler reaches the release hook 26 as shown in Fig. 5. Due to the inclined surface on the release hook, the rollers 32 engage the latter causing the coupler to ride outwardly from the tooth and out of the path of the latter. The rollers then ride upon the outer side of the rim of the sheave, and the pins 34 are positioned to follow the outside of rails 25a. The pull upon the handle of the tongs 20 45 caused by the counter-weight line 22, will cause the line and coupler to be returned to its initial position, the follower pins 34 maintaining the coupler out of tooth engaging position and the coupler being returned to the position shown in Fig. 3. If tension is 50 maintained upon the control line, the cat-head will again pick up the coupler and repeat the movement. Where a repetition of the movement is desired, it is convenient to hook the ring 41 on the control line over the hook 42, and movement of the rope 21 will be repeated causing oscillation of the tong handle. This movement will continue until the tension upon the control line is released, 55 which is accomplished by unhooking the ring from hook 42. If a single movement of the rope 21 is desired, it is merely necessary to hold tension upon the control line until the movement has been started and then to release the pull upon the control line.

What I claim is:—

1. A cat head structure comprising a winding member having a winding surface for a line, a coupler abutment on said surface, a line to be wound on said member having a coupler for engagement with said coupler abutment whereby said line may be anchored to said winding member, a release member in the path of said coupler abutment to disengage said coupler from said coupler abutment, retaining means extending along said winding surface and ending at said release member to maintain said coupler in coupling position, and means to initially place said coupler in engagement with said coupler 80 abutment and retaining means. 75

2. A cat head structure comprising a winding member having a winding surface for a line, a coupler abutment on said surface, a line to be wound on said member having a coupler for engagement with said coupler abutment whereby said line may be anchored to said winding member, a release member in the path of said coupler abutment to disengage said coupler from said coupler abutment, retaining means extending along said winding surface and ending at said release member to maintain said coupler in coupling position, and control means to initially support said coupler out of engagement with 95 said coupler abutment and retaining means, said control means being movable to place said coupler in engagement position for said coupler abutment and retaining means. 90

3. A cat head structure comprising a 100 winding member having a winding surface for a line, a coupler abutment on said surface, a line to be wound on said member having a coupler for engagement with said coupler abutment whereby said line may be 105 anchored to said winding member, a guide for said coupler extending partially along the winding surface path to maintain said coupler in coupling position or out of coupling position, means at one end of said guide 110 to initially move said coupler into engagement with said coupler abutment and in coupling placement with said guide, and a release member in the path of said coupler at the other end of said guide to lift and disengage said coupler from said coupler abutment and dispose said coupler on said guide in uncoupling placement. 115

4. A cat head structure comprising a winding sheave, a coupler tooth in a flange 120 of said sheave, a line having a coupler for engagement by said tooth whereby to anchor said line to said sheave, a frame partially encompassing said sheave, said frame having a release member to engage said coupler and lift the latter from engagement with said tooth at the end of its travel along said frame, there being an entry end on said frame, retaining rails on said frame to maintain said coupler in engagement with said 125 130

tooth during travel of said coupler from the entry end of the frame to said release member, and means to initially place said coupler in engagement with said tooth and said retaining rails.

- 5 5. A cat head structure comprising a winding sheave, a coupler tooth in a flange of said sheave, a line having a coupler for engagement by said tooth whereby to anchor said line to said sheave, a frame partially encompassing said sheave, said frame having a release member to engage said coupler and lift the latter from engagement with said tooth at the end of its travel along said frame, there being an entry end on said frame, guide rails on said frame to maintain said coupler in engagement with said tooth during travel of said coupler from the entry end of the frame to said release member and to maintain said coupler out of coupling position on return travel, and means to initially place said coupler in engagement with said tooth and said retaining rails in coupling placement position, said release member being disposed to place said coupler in uncoupling position on said rails.

6. A cat head structure comprising a winding sheave, a coupler tooth in a flange of said sheave, a line having a coupler for engagement by said tooth whereby to anchor said line to said sheave, a frame partially encompassing said sheave, said frame having a release catch to engage said coupler and lift the latter from engagement with said tooth at the end of its travel along said frame, there being an entry end on said frame, guide rails on said frame, said coupler having followers to ride on the inner side of said rails and maintain said coupler in engagement with said tooth during travel of said coupler from the entry end of the frame to said release catch and to ride on the outer side of said rails and maintain said coupler out of engagement with said tooth on return to initial position, and control means normally supporting said coupler out of engagement with said tooth and operable to initially place said coupler in engagement with said tooth and with its followers on the inner side of said guide rails.

7. A cat head structure comprising a winding sheave, a coupler tooth in a flange of said sheave, a line having a coupler hook for engagement by said tooth whereby to anchor said line to said sheave, a frame partially encompassing said sheave, said frame having a release catch to engage said coupler and lift the latter from engagement with said tooth at the end of its travel along said frame, there being an entry end on said frame, guide rails on said frame, said coupler having followers to ride on the inner side of said rails and maintain said coupler in engagement with said tooth during travel of said coupler from the entry end of the frame

to said release catch and to ride on the outer side of said rails and maintain said coupler out of engagement with said tooth on its return to initial position, and a control catch upon which said coupler rests, said control slide being normally positioned to hold said coupler out of engagement with said tooth and being movable to initially place said coupler in engagement with said tooth and with its follower on the inner side of said rails.

In witness that I claim the foregoing I have hereunto subscribed my name this 30th day of April, 1930.
